HOUSING FOR A MICROSCOPE UNIT

Kenneth D. Maier, Mendon, N. Y., assignor to Bausch & Lomb Optical Company, Rochester, N. Y., a corporation of New York

Application April 2, 1958, Serial No. 50,295

Term of patent 14 years

(Cl. D57—1)

Fig. 1 is a rear perspective view of a housing for a microscope unit showing my new design. The side not shown is the same as the side shown.

Fig. 2 is a front perspective view thereof.

The dominant features of my design are shown in full lines on the drawing.

I claim:
The ornamental design for a housing for a microscope unit, substantially as shown and described.
